UNITED STATES PATENT OFFICE.

FRANK J. WALKER, OF WICHITA, KANSAS.

SHOE-HEEL.

1,395,535.

Specification of Letters Patent.

Patented Nov. 1, 1921.

Application filed December 27, 1920. Serial No. 433,143.

To all whom it may concern:

Be it known that I, FRANK J. WALKER, a citizen of the United States, residing at Wichita, in the county of Sedgwick and State of Kansas, have invented certain new and useful Improvements in Shoe-Heels, of which the following is a specification.

This invention relates to improvements in resilient heel lifts and has as one of its 10 objects to provide a resilient heel lift which may be readily applied to a heel and secured in place by a single fastening element.

Another object of the invention is to provide a resilient heel lift which, while adapted 15 to be secured in place by a single fastening element, will be snugly held in place against the under face of the heel to which it is applied and in a manner, if desired, to permit of its rotation so as to insure of its being 20 worn away evenly, in use, instead of being worn down unevenly as is usually the case.

Another object of the invention is to provide a resilient heel lift so reinforced as to render the same more substantial than lifts 25 of the usual construction and at the same time equally as yieldable and resilient.

Another object of the invention is to provide a lift which will be more durable and longer lasting than the majority of resilient 30 heel lifts, as ordinarily constructed.

In the accompanying drawing:

Figure 1 is a horizontal sectional view through the heel lift embodying the present invention applied to a shoe heel which latter is shown in bottom plan;

Fig. 2 is a vertical sectional view taken substantially on the line 2—2 of Fig. 1.

In the drawing, the numeral 1 indicates the leather heel of a shoe and the numeral 2 40 indicates in general the resilient lift embodying the invention and which lift is secured to the under face of the heel 1 and is to constitute the wearing surface of the heel.

The heel lift 2 is preferably formed of soft 45 rubber, although it may be made of a composition of materials, if desired, but in any event it will preferably be resilient or yieldable so as to cushion the impact of the heel 50 with the ground surface. The lift comprises a body which is indicated by the numeral 3 and which is preferably of circular form, the body having flat upper and under faces and having its last mentioned face 55 roughened, if desired, so as to provide

Embedded in the body 3 at the time of manufacture, is a retaining element which is indicated in general by the numeral 4 and this element is preferably formed from a 60 suitable resilient wire material which is so fashioned as to provide a central eye 5 about which as a center the length of wire is coiled, the coiled portion of the wire being indicated by the numeral 6. The wire may be 65 given any desired number of turns or coils about the eye 5 and the coils may begin directly at the eye or the wire may be extended for a short distance tangentially from the eye 5 as indicated by the numeral 7, before being bent into coiled form. The wire, at the outer end of its coil portion 6, is preferably bent back upon itself to form a loop or eye 8 which provides a blunt end not liable to work through the rubber body 70 3, as might happen if the coiled portion terminated in a pointed end. By reference to Figs. 1 and 2 of the drawings it will be observed that all portions of the retaining element 4 are located substantially in a common plane and that the eye 5 of the said element is located axially with relation to the body 2 of the lift.

In the specific embodiment of the invention illustrated in the drawings, the resilient wire from which the retaining member is formed is extended tangentially from the circular eye 5, as indicated by the numeral 7 and as previously explained, and is thence turned back upon the portion 7 and in the 90 form of a volute curve and finally terminates in the eye portion 8 in forming which the end portion of the wire is bent outwardly and back upon itself.

Preferably the underside of the lift body 95 2 is formed with a countersink or recess 9 at the point of location of the eye 5, and the said body is further formed with an opening or perforation 10 in registration with and concentric to the said eye and passing 100 through the body so as to accommodate a securing element such for example as a screw 11, the shank of which screw fits through the eye 5 and is threaded into the leather heel 1, the head 12 of the screw engaging the underside of the eye 5 and being housed within the recess or countersink 9, as clearly illustrated in Fig. 2 of the drawing. This screw 11, or any other appropriate fastening element employed, constitutes the sole means 105 for securing the heel lift in place upon the under face of the heel 1 and by reason of

the engagement of its head against the eye 5, a firm and secure connection is provided and yet the resiliency of the lift is in no way impaired. Furthermore the lift is in 10 5 this manner mounted so that it may turn more or less freely about the securing element as a center and therefore in use the lift will be in fact turned from time to time so that all portions thereof will receive equal 15 10 wear and the lift will therefore not become worn down upon one side more than upon another. It will also be evident that any tendency to pull the lift away from the shoe heel is resisted by the resiliency of the retaining member 4 so that the lift is held permanently snugly against the under face of the shoe 1 not only at its central point of attachment but also at its peripheral portion. It will also be evident that inasmuch as the 20 20 retaining member 4 is embedded in the heel lift, this member will not be exposed until the lift has been worn down to a very considerable extent, so that the life of the lift is materially prolonged and the lift is rendered more durable. Also it will be evident 25 25 that the retaining member reinforces the lift.

While all portions of the retaining element may be said to occupy substantially a common plane, nevertheless it may be desirable 30 30 to spring the eye at the center of the member inwardly to a slight degree as illustrated in Fig. 2, so that the head of the securing element may be positioned as far as possible 35 35 from the tread face of the lift 2.

Having thus described the invention, what is claimed as new is:

1. A heel lift comprising a resilient body,

and a retaining element embedded centrally therein and comprising a resilient coil having a central eye for the passage of a securing element. 40

2. A heel lift comprising a resilient body, and a retaining element associated with the body centrally thereof and comprising a resilient coil having an opening for the passage of a securing element. 45

3. A heel lift comprising a resilient body, and a retaining element embedded therein and having a central eye for the passage of a securing element, the retaining element having a resilient portion arranged in a coil about the said eye. 50

4. A heel lift comprising a resilient body, and a retaining element embedded therein 55 and having a central eye for the passage of a securing element, the retaining element having a resilient portion arranged in a coil about the said eye and terminating in a blunt end. 60

5. A heel lift comprising a resilient body, and a retaining element embedded therein and having a central eye for the passage of a securing element, the retaining element having a resilient portion arranged in a coil 65 about the said eye and terminating in an eye portion occupying the plane of the coil. 60

6. A heel lift comprising a resilient body, and a retaining element embedded therein and comprising a resilient coil provided at 70 its inner end with an eye for the passage of a securing element and having its outer end bent back upon itself, all portions of the said element occupying a common plane.

In testimony whereof I affix my signature. 75
FRANK J. WALKER. [L.S.]
